UNITED STATES PATENT OFFICE.

JOHN T. HAWKINS, OF TAUNTON, MASSACHUSETTS.

SHEET-DELIVERY APPARATUS FOR PRINTING-PRESSES.

SPECIFICATION forming part of Letters Patent No. 257,575, dated May 9, 1882.

Application filed November 26, 1880. (No model.)

To all whom it may concern:

Be it known that I, JOHN T. HAWKINS, of Taunton, in the county of Bristol and State of Massachusetts, have invented a new and useful Improvement in Sheet-Delivery Apparatus for Printing-Presses, which improvement is fully set forth and illustrated in the following specification and accompanying drawings.

The invention consists primarily in the employment of frictional-surfaced sheet-driving wheels driven at the same peripheral velocity as that of the impression-cylinder, and so placed as to touch or act upon the unprinted margins of the sheets of paper only, the said frictional-surfaced wheels being surrounded in part by sheet-guides touching or nearly touching their frictional peripheries.

The invention also consists in the employment of a revolving fan or equivalent device, in combination with the sheet-driving wheels and sheet-guides above mentioned, whereby a current of air is caused to impinge upon the last-printed side of the sheet as it is being discharged from said guides, thereby causing each sheet to float upon or remain suspended in the air at said time.

The invention also consists in the employment of a fly consisting of a hollow fly-shaft provided with hollow perforated fly-fingers for the purpose of allowing a current of air to flow in jets through the said fingers of the fly.

The invention further consists in the employment of an air-pump actuated simultaneously with and suitably connected to a hollow fly-shaft provided with hollow perforated fly-fingers, from the perforations in which fingers jets of air are ejected by said pump in order to prevent contact between the printed side of the sheet and the fly-fingers while the sheet is being conveyed by the fly over to and upon the fly-board.

All of the above-mentioned mechanism, with its necessary adjuncts, is hereinafter described in detail, as follows:

In the accompanying drawings, Figure 1 illustrates in side elevation the mechanism designed to effect the method herein described of delivering the printed sheets, showing in addition such adjunct parts of a cylinder printing-press as are essential to the illustration of the invention. Figs. 2 and 3 illustrate a rear

elevation and plan, respectively, of the same mechanism, the feed-board and driving belt in Fig. 3 being omitted. Fig. 4 illustrates in two views the sheet-driving wheels and their construction. Fig. 5 illustrates in two views the cam which operates the sheet-lifter fingers of the machine, and Fig. 6, also in two views, the lever by means of which motion is transmitted to said lifter-fingers from the cam illustrated in Fig. 5. Figs. 1 and 3 are drawn upon a smaller scale than that used in drawing Figs. 2 and 4.

In the said figures, the letters A A indicate parts of the side frames of a cylinder-press, 65 the letter B the impression-cylinder, and C the feed-board.

C' indicates the fly-board, and D the shaft, carrying the cylinder-grippers y in the usual manner.

D' and d indicate respectively the cam and spring with its rod, for operating the grippers y when engaging their opening-stud d' and their closing-stud d².

E indicates a shaft extending across the cylinder, carrying a series of sheet-lifter fingers, f², over the ends of which the leading edge of the sheet is clamped by the cylinder-grippers y.

To the end of the shaft E is secured a two-armed lever, f, carrying on one arm a pin, g', 80 and on the other arm a pin, g², engaging a spring, h', on the inside of the flange of the cylinder-head. The pin g' engages the stationary cam F, secured to the frame of the machine, in passing up whose inclined face said pin lifts the sheet-lifter fingers f² simultaneously with the opening of the cylinder-grippers y.

R indicates a rod extending across the press and attached to the frames A A, upon which 90 the sheet-guides R' are secured by means of set-screws in such manner that they may be set at any desired point in the width of the press to suit the size of sheet to be printed, the said guides forming on their respective inside 95 curves a circular arc corresponding to the periphery of the sheet-driving wheels a a. The number of the guides R' to be used depends upon the width of press or sheet to be printed.

A' indicates a shaft journaled in the frames 100 of the press, and carrying inside the frames two or more narrow sheet-driving wheels, a a,

- having an elastic frictional surface, of rubber or other suitable material, a' , upon their peripheries, preferably in the form shown in Fig. 4, in which is a series of segments of sheet-rubber, a' , held to the conical or beveled faces of the wheels a by means of the clamps a^2 and screws a^3 . The rubber is thus presented edge-wise to the moving sheet. Any deflection or stretching that may be exerted upon said rubber segments will tend outwardly, thereby keeping the sheet tightly stretched in a direction across the press, as but two of the wheels a are generally used, and these so placed as to come in contact with the outer margins 15 of the paper only. The sheet-driving wheels a are placed in line with the corresponding sheet-guides, R' , the said wheels being capable of adjustment across the machine, as are also the said guides.
- 20 On a continuation of the shaft A' , outside of the frame of the machine A , is secured a pulley, c , and upon the impression-cylinder's axis a corresponding pulley, c' , is secured, said pulleys being so proportioned as to give to the 25 frictional-surfaced sheet-driving wheels a and the impression-surface of the cylinder B the same peripheral velocity. The shaft A' is so placed with reference to the axis of the cylinder B that the frictional periphery a' of the 30 wheels a will press lightly upon the impression-surface of the cylinder B , a crossed belt, B' , or equivalent gearing, giving these respective surfaces motion in the same direction and at the same velocity. The sheet-guides R' are 35 polished on their interior curved surfaces, so that the back of the sheet will slide freely upon them, while the pressure of the elastic frictional periphery a' of the sheet-driving wheels a upon the margins of the last-printed side con- 40 veys each sheet to the point at which it is taken by the fly-fingers F^2 , and by them carried over to and deposited upon the fly-table C' , the fly being actuated by means of the cam i , the lever L , the belt H , and the spring V . Any 45 number of the sheet-guides R' may be used suitable to the work to be done or to the width of the press, as has been before stated in reference to the sheet-driving wheels a ; but generally and preferably but two of each of said 50 wheels and guides are used, which are so placed crosswise the press as to bring their frictional surfaces in contact only with the unprinted margins which nearly all printed work has left at its sides; but, as said guides R' come 55 in contact only with the unprinted or dry side of the sheet, additional intermediate guides may be placed, if desired, between the two extreme guides which correspond with the marginal sheet-driving wheels.
- 60 F' indicates a small fan secured to a shaft, s , journaled in the frame A , which fan is driven by a belt, B^2 ; but any other suitable means of driving the same may be employed, and instead of a fan any other suitable means of producing a current or blast of air at this point 65 may be employed.

S indicates a hollow shaft, provided with a series of hollow fly-fingers, F^2 , perforated on their faces, as shown at F^3 , and secured to said shaft by cored clamps, as shown at c^2 . The hollow shaft S has secured thereon a hollow disk, D^2 , with whose interior the interior of said shaft communicates; and near the rim of said disk, like a crank-pin or stud, is secured the hollow trunnion T of the air-pump cylinder P . The said air-pump is single-acting, and one of its covers acts as a guide for its piston-rod p , which cover is also perforated to permit of the free ingress and egress of air therethrough. At the opposite end of the air-pump its chamber communicates with the interior of the disk D^2 by means of the hollow trunnion T , secured thereto, as above described. 75

H indicates a belt, one end of which enwraps the disk D^2 , the other end being attached to 80 the rocker-lever L , pivoted to the frame A at A^2 . The said lever, when operated by the cam i and interposed roller r , actuates the fly F^2 in its forward or delivery motion through the interposed belt H and disk D^2 , secured to the 85 fly-shaft S . The return motion of the fly F^2 is effected by means of the spring V and its rod V' , secured at its respective ends to the crank-pin V^2 of the disk D^2 , and to the frame of the press. It thus appears evident that the operation 90 which causes the forward or delivery motion of the fly also causes at the same time the oscillation of the air-pump P , and consequently a compression of the air within the chamber of the pump between its closed end 95 and its piston, whose rod p is pivoted to the frame at p' —the point upon which the air-pump P oscillates. The air thus compressed is necessarily forced in a strong current through the hollow trunnion T into the hollow disk D^2 , 100 thence into the hollow shaft S , thence into the hollow fingers F^2 , and finally out of the perforations F^3 therein. Upon the return motion 105 of the fly, disk, and air-pump the air enters the perforated fingers F^2 and resupplies the 110 air-pump P . A suitable valve, however, opening inwardly, may be placed, if desired, in the air-pump cover or in its piston for the purpose 115 of a resupply of air to the pump. The fan F' and the fly F^2 may be quickly removed from 120 their bearings, together with their shafts, by means of the couplings K K' , provided for such purpose, their respective shafts being severed at said couplings, as indicated in dotted lines in Figs. 2 and 3.

The complete operation of this machine is as follows: The sheet to be printed, being taken from the feed-board C in the usual manner by the cylinder-grippers y , which clamp the leading edge of the sheet over the points of 125 the lifter-fingers f^2 , is carried around to the type-bed and through the process of receiving the impression. Upon arriving at the point x of the sheet-guides R' the grippers y release the sheet by the engagement of the gripper-tumbler cam D' with the opening-stud d' , the sheet at this point being kept from dropping 130

back upon the form by being held between the cylinder B and the periphery a' of the sheet-driving wheels a , the advancing edge of the sheet having passed their point of contact before the grippers open. Simultaneously with the opening of the grippers the lever f is operated by the cam F, which causes the sheet-lifter fingers f^2 under the edge of the sheet to lift up from the cylinder-surface the advancing edge 5 of the sheet, which edge thus passes between the guides R' and the sheet-driving wheels a , whence the sheet is carried continuously forward until its advancing edge has passed down in front of the fly-fingers F² and its following 10 edge has passed beyond the point x' of the sheet-guides R'. While the sheet is thus passing down in front of the inclined fly-fingers F², at rest, the current of air from the revolving fan F' buoys up or floats the sheet in the 15 air and prevents it from touching said fingers. When the following edge of the sheet has passed beyond the point x' of the sheet-guides R' the fly F², by the proper adjustment of the cam i, passes over to the fly-table C', carrying 20 with it the sheet, and simultaneously with this movement of the fly the air-pump P forces a current of air into the fly, which current is projected in jets out of the perforations F³ in the fly-fingers, thereby preventing while in 25 transit the contact of the sheet with the fly during its part of the delivery operation. After thus depositing a sheet upon the fly-board C' the fly F² returns to make another delivery by the time that the advancing edge of the 30 succeeding sheet passes out from the point x' between the sheet-guides R' and the sheet-driving wheels a . The fly F² is returned after each delivery of a sheet to its position for a new delivery by means of the spring V, its rod 35 V', and the crank-pin V², attached to the hollow disk D², as already explained.

By the method of delivery above described each sheet is delivered with its last-printed side upward without the use of tapes or cords, 40 without the necessity of having a leading margin of sheet so wide as to overhang the gripper-edge of the impression-cylinder, and without bringing any part of the printed surface 45 of a sheet in contact with any part of the delivery mechanism, while at the same time, from the great facility afforded for the quick detachment of the fan and fly, and with but two sheet-driving wheels at the side margins only 50 of the sheets, the back of the press is rendered free and clear for the purposes of access to the 55 form.

I do not limit myself to the means herein shown and described for imparting the requisite movements to the sheet-lifter fingers f^2 , the frictional sheet-driving wheels a , the fan F', the fly F², and the air-pump P, as the means for imparting said movements may be varied to suit the particular form and proportions of press to which such parts may be applied without departing from the principles 65 of this invention; and any of the well-known

devices for effecting like motions may be employed, as may be most convenient to the end sought.

I do not herein claim as new, *per se*, any of the mechanism shown and described for effecting the above-mentioned movements; but, as of my invention,

I claim—

1. In a cylinder printing-press or other machine requiring a similar disposition or delivery of sheets of paper therefrom, the combination of frictional-surfaced sheet-driving wheels suitably spaced upon a common axis, and curved sheet-guides in contact with and conformed to the peripheries of said wheels and rigidly mounted upon a shaft above the same, all arranged and operating substantially as and for the purposes set forth. 75

2. In a cylinder printing-press or other machine requiring a similar disposition or delivery of sheets of paper therefrom, frictional-surfaced sheet-driving wheels suitably spaced upon a common axis, and curved sheet-guides in contact with and conformed to the peripheries of said wheels, and rigidly mounted upon a shaft above the same, in combination with means, substantially as described, to force a current of air upon the last-printed side of each sheet of paper when discharged from between said wheels and guides, substantially as and for the purposes set forth. 85

3. In a cylinder printing-press or other machine requiring a similar disposition or delivery of sheets of paper therefrom, the combination of frictional-surfaced sheet-driving wheels suitably spaced upon a common axis, curved sheet-guides in contact with and conformed to the peripheries of said wheels and rigidly mounted upon a shaft above the same, 100 a revolving fan, and an oscillating fly, all arranged and operating substantially as and for the purposes set forth. 105

4. In a cylinder printing-press or other machine requiring a similar disposition or delivery of sheets of paper therefrom, a fly or delivery-frame consisting of an oscillating or vibrating hollow shaft having secured thereto hollow perforated bars or fingers, and provided with means, substantially as described, 110 for forcing a current of air through perforations in said fingers, substantially as and for the purposes set forth. 115

5. In a cylinder printing-press or other machine requiring a similar disposition or delivery of sheets of paper therefrom, in combination with a revolving fan, a fly or delivery-frame consisting of an oscillating or vibrating hollow shaft having secured thereto hollow perforated bars or fingers, and provided with means, substantially as described, 120 for forcing a current of air through perforations in said fingers, substantially as and for the purposes set forth. 125

6. In a cylinder printing-press or other machine requiring a similar disposition or delivery of sheets of paper therefrom, in combina- 130

tion with a hollow fly-shaft having hollow perforated fingers, an air-pump connected thereto, whereby a current of air is forced through the perforations in said fingers during the forward 5 or delivery oscillation of the fly, substantially as and for the purposes set forth.

7. In a cylinder printing-press or other machine requiring a similar disposition or delivery of sheets of paper therefrom, the combination of frictional-surfaced sheet-driving wheels suitably spaced upon a common axis, curved sheet-guides in contact with and conformed to the peripheries of said wheels and rigidly mounted upon a shaft above the same, 10 an oscillating hollow fly-shaft provided with hollow perforated fingers, and an air-pump, all arranged and operating substantially as and for the purposes set forth.

8. In a cylinder printing-press or other machine requiring a similar disposition or delivery of sheets of paper therefrom, the combination of frictional-surfaced sheet-driving wheels suitably spaced upon a common axis, curved sheet-guides in contact with and conformed to the peripheries of said wheels and 20 rigidly mounted upon a shaft above the same, a revolving fan, a hollow fly-shaft provided with perforated fingers, and an air-pump, all arranged and operating substantially as and for the purposes set forth.

JOHN T. HAWKINS.
